UNITED STATES PATENT OFFICE

ISAAC BOWE, OF CHICAGO, ILLINOIS.

AUTOMATIC-STOKING FURNACE.

SPECIFICATION forming part of Letters Patent No. 532,759, dated January 22, 1895.

Application filed April 5, 1894. Serial No. 506,515. (No model.)

To all whom it may concern:

Be it known that I, ISAAC BOWE, of Chicago, in the county of Cook and State of Illinois, have invented certain new and useful Improvements in Automatic-Stoking Furnaces, of which the following is a full, clear, and exact description, reference being had to the accompanying drawings, forming a part of this specification, in which corresponding letters of reference in the different figures indicate like parts.

The object of my invention is to provide a furnace to which the fuel may be fed automatically and in such manner as to be uniformly and evenly distributed over the grate surface.

To this end, my invention consists in certain novel features relating to the construction of the grate itself as well as in the means provided for feeding the fuel thereto—all of which is hereinafter more specifically described and designated in the claims.

In the drawings Figure 1, is a front elevation of a furnace embodying the features of my invention. Fig. 2, is plan view of a portion thereof. Fig. 3, is a side view of the parts shown in Fig. 2. Fig. 4, is a plan view of the grate and the mechanism for operating the same. Fig. 5, is a longitudinal sectional view taken upon the line 5—5, Fig. 4. Fig. 6, is a plan view showing a modification of the feeding mechanism. Fig. 7, is a sectional detail view taken upon the line 7—7, Fig. 6. Fig. 8, is a face view in detail showing my improved means for tilting the grate-bars. Fig. 9, is a plan view in detail for still further modification of the feeding mechanism, and Fig. 10, is a side view of the same in section, taken upon the line 8—8, Fig. 9.

Referring to the drawings, *a* represents the frame or casing of the furnace over which is placed the usual boiler *b*, Figs. 1, 2, and 5. The furnace is preferably extended forward beyond the front of the boiler as more clearly shown in Fig. 5, in order that the fuel may be uniformly fed from the outside to the middle of the grate surface.

The grate, which is located at the forward end of the boiler, as is usual in boiler furnaces, consists of an annular ring *c*, which is mounted upon and supported by a series of rollers *d* secured in adjustable brackets *e*, Fig.

5. The brackets have each an oblong opening *e'* therein which are adapted to receive a rigid supporting arm *e* which is formed upon or rigidly secured to an annular supporting ring *f'* set in the brick-work which forms the furnace setting. By means of wedges *e* placed above the arms *e* as shown, the brackets *e* may be raised or lowered as desired which enables the ring *c* to be accurately leveled. The brackets may then be firmly secured in place by means of set-screws *e*.

The supporting ring *f'* constitutes an important feature of my invention inasmuch as it enables the grate to be kept in its proper position regardless of the uneven settling or warping of the furnace walls. It is made in sections rigidly attached to each other, and is provided with one or more flanges *f* which are set in the masonry thereby being protected from heat. These flanges serve to sustain the ring in position and impart lateral strength thereto. The ring, moreover, built thus into the wall, prevents the latter from warping or settling unevenly.

The ring *c* is free to revolve upon the roller bearings and the bottom thereof is beveled as indicated, in order to maintain its position upon the rollers. Within the ring *c* is formed a series of horizontal openings *f* for the reception of the ends *g* of the grate-bars *h*. The ends or extensions of the bars are smaller in cross-section than the bars themselves, so that shoulders are formed upon the latter in such a manner as to permit of an endwise movement of the bars, while at the same time the movement is limited in extent. The openings *f* are also of sufficient depth to permit the bars to be raised and lowered for the purpose hereinafter set forth.

The outer circumference of the ring *c* is provided with teeth *i* which are adapted to be engaged by a worm gear *j* upon a shaft *k*, Figs. 1, 4, 5 and 7, which is mounted in suitable bearings upon the casing as shown, and is provided with a sprocket wheel upon the end which is connected by means of a sprocket-chain *l* to a suitable source of power. The rotation of the shaft *k* serves to rotate the grate continuously.

Rigidly attached to the casing *a* is a bracket *m*, Figs. 1, 2 and 4 in a slot in which is loosely secured a sliding bearing block

which is held in a normal position by means of a spiral spring n indicated in dotted lines in Fig. 4. The bearing-block m , which is not shown, serves as a support for a roller o which is adapted to bear against the protruding ends of the grate-bars as clearly shown in Fig. 4, and to push them in one by one as they are brought in contact with it by the rotation of the grate,—thus serving to loosen the ashes and cause them to drop into the ash-pit. Should the grate-bar fail to slide upon its first contact with the roller o the spring n permits the roller to yield until the bar is brought into more complete alignment with the axis of the roller when the spring, by reason of its more direct action, overcomes the friction of the bar and causes the latter to slide back suddenly, which serves to free the ashes therefrom more completely.

Should the sliding action of the bars prove insufficient to clear the grate surface, I have provided the following means for automatically tilting the bars: Pivoted to the casing at p , Figs. 1 and 8, is a bar q to which is secured upon a horizontal axis a roller q' which is adapted to engage with and lift the projecting end of the grate-bars as the ring is rotated. The opposite end of the bar q is arranged to rest upon a spring r having a set-screw beneath it for the purpose of adjusting its tension. The tendency of this device is to tilt each bar suddenly as it passes over the roller and thereby aid in keeping the grate clear.

Above the grate is located a hopper shaped ring s , Figs. 4 and 5, which is preferably made in sections as indicated to prevent warping and permit of replacement, and which serves to direct the fuel upon the grate as well as to prevent the ring c from becoming overheated.

Having described the construction of and means for operating my improved grate, I will now describe my improved automatic mechanism for feeding the fuel thereto.

Located upon the casing above the furnace and in front of the boiler, is a hopper t , Figs. 1, 2, 3 and 5, which is wider at the left than at the right-hand side in order to hold a quantity of fuel proportionate to the varying feed.

Beneath the hopper is preferably arranged a series of feeding plungers $t' t'' t'''$ which, when reciprocated, serve to push the fuel out through openings at the rear of the hopper upon a trap door u which is secured to a rock-shaft u' mounted in suitable bearings as shown. A counterpoise weight U^3 serves to balance the trap-door and return it to its normal position.

Mounted in bearings upon the front of the casing is a rock-shaft v provided with an arm v' which is connected by means of a pitman v^2 to a crank-pin upon a gear wheel w , which meshes into a pinion upon the shaft k . It will thus be seen that by virtue of the rotation of the shaft k the shaft v is continually rocked through the action of the mechanism described.

Rigidly attached to the rock-shaft v are

arms v^3 , to which is secured a connecting-rod v^4 with which each of the plungers $t' t'' t'''$ is connected by means of bars t^5 . Each of the bars t^5 is bent downwardly at its outer end as shown at t^6 , Fig. 5, so as to engage with the rod v^4 . A clamp t^7 is adjustably secured to each of the bars t^5 . By means of this arrangement the forward movement of the feeding plungers may be varied and adjusted to any desired extent, the vibration of the arms v^3 being constant.

In Fig. 2 I have shown the feeding plungers as occupying different relative positions, that to the left indicating the maximum, and that to the right indicating the minimum movement. A sliding bar v^5 is pivotally attached to the rod v^4 and extended forward in operative proximity to a stud u^2 which is rigidly attached to the rod u' upon which the trap door is pivoted. A shoulder v^6 upon the bar v^5 is adapted to engage with the stud u^2 and tilt the trap door as indicated in Fig. 3 when the bar v is carried forward to its full limit, thus discharging the fuel which is thrust forward upon the trap-door into the furnace. The length of the trap door is equal to about half the diameter of the grate; and is so arranged that when the fuel is discharged therefrom it falls in a line extending from the center of the grate to the outer edge,—the changes being delivered in the same order from the smallest to the largest. As the grate is being constantly rotated by the worm j it follows that each charge of fuel is dropped upon a fully ignited fire and not upon fresh fuel. Moreover, the charges being graduated from the center of the grate outwardly it follows that a uniform depth of fuel must be constantly maintained and hence that a uniform fire may be constantly secured. In order that the feed may be adjusted to vary the aggregate amount of fuel fed within a given time, I provide a slot v^7 in the arm v' and adjust the wrist-pin v^8 therein by means of suitable lock-nuts so as to change its distance to any desired extent from the rod v . By this means the rod v may be tilted to a greater or less extent according to the amount of fuel desired to be fed to the furnace.

In lieu of the reciprocating plungers, it is obvious that the rock shaft and the adjustable sliding bars t^5 may be employed to actuate a series of rotary buckets or a series of worm conveyers so as to feed the fuel uniformly upon the grate surface.

In Figs. 6 and 7, a series of rotary buckets x is shown mounted upon an axis at the bottom of the hopper. Each bucket is arranged to rotate independently of its fellow, by means of ratchet-wheels x' secured to each bucket and in operative connection with pawls as shown, which are in turn connected with the bars t^5 . The buckets are divided into compartments, and the extent to which the bar t^5 is permitted to move determines the size of the charge delivered thereby.

In Figs. 9 and 10, I have shown spiral con-

veyers *y* upon the shafts of which are mounted ratchet-wheels *x* which are operated by means of pawls in connection with the bars *t*; said bars and the operating parts therefor being 5 differently located.

The gearing by which the feeding mechanism is actuated is so timed with reference to the rotation of the grate by the worm-gear that the charges dumped upon the grate surface 10 during one revolution will lie in different radial lines from those deposited during the preceding revolution so that the distribution will be uniform instead of being in radial ridges. This result is accomplished by so apportioning the teeth in the respective gears 15 that one is not divisible by the other.

By actuating a single grate-bar at a time it is obvious that much less power is required than for shaking the entire grate. The feeding mechanism also is adapted to be actuated by a minimum expenditure of power.

My improved furnace is adapted to the use of coal as well as shavings, saw-dust or other kinds of finely divided fuel. By its use the 25 fuel may be uniformly fed at all times, the formation of smoke may be effectually prevented, and a uniform incandescent fire may at all times be maintained throughout the entire grate surface.

Having thus described my invention, I claim—

1. The combination with a furnace of a rotary grate, means for actuating the same, a fuel feeding magazine in operative proximity to an opening above the grate, a series of independent fuel measuring and discharging receptacles arranged in said magazine, a rock-shaft in operative connection with a source of power, means for actuating said rock-shaft at regular intervals and means for connecting said measuring receptacles with said rock-shaft, substantially as set forth.

2. The combination with a furnace of a rotary grate, means for actuating the same, a fuel magazine in operative proximity to an opening above the grate, a series of independent fuel measuring and discharging receptacles of varying capacity arranged in said magazine, a rock-shaft in operative connection with a source of power, means for actuating the same at regular intervals and means for independently and detachably connecting

said measuring receptacles with said rock-shaft, whereby one or more may be actuated at the will of the operator, substantially as described.

3. The combination with a furnace of a rotary grate, means for actuating the same, a fuel magazine in operative proximity to an opening above the grate, a series of independent fuel measuring and discharging receptacles arranged in said magazine, a rock-shaft in operative connection with a source of power for actuating the same at regular intervals, means for independently connecting said measuring receptacles with said rock-shaft and means for adjusting said respective connections to vary the extent of movement thereof, substantially as described.

4. The combination with a furnace having a rotary grate of a fuel magazine, a series of fuel discharging devices in operative connection therewith, a rock-shaft, means for actuating the same, bar *v* in operative connection with said rock-shaft and the connecting bars *t* having adjusting clamps *t* thereon, substantially as described.

5. The combination in a self feeding furnace, of a magazine, a series of fuel discharging devices in operative connection therewith, a rock-shaft connected with said fuel discharging devices, a source of power, and an adjustable connection between the same and said rock-shaft for varying the extent of movement of the latter, whereby all the charges may be increased or diminished, substantially as described.

6. The combination in a self feeding furnace of a magazine, a series of fuel discharging devices, a counterpoised trap door for receiving the fuel charges, a rock-shaft connected with said fuel discharging devices, a source of power for periodically tilting said rock-shaft, and a tripping device interposed between said rock-shaft and said trap-door, substantially as described.

In testimony whereof I have signed this specification, in the presence of two subscribing witnesses, this 23d day of March, 1894.

ISAAC BOWE.
